Primary Examiner — Karen S Acker(74) Attorney, Agent, or Firm — Dentons US LLP(57) CLAIM

The ornamental design for a quilted fabric, as shown and described.

DESCRIPTION

A portion of the disclosure of this patent document contains material which is or may be subject to copyright protection. The copyright owner has no objection to the facsimile reproduction by anyone of the patent document or patent disclosure, as it appears in the Patent and Trademark Office patent file or records, but otherwise reserves all copyright rights whatsoever.

FIG. 1 is a plan view of quilted fabric embodying the design;

FIG. 2 is a perspective view thereof;

FIG. 3 is a front edge view thereof;

FIG. 4 is a back edge view thereof;

FIG. 5 is a right side edge view thereof; and,

FIG. 6 is a left side edge view thereof.

The broken lines depict both portions of the quilted fabric and boundaries to the claim. The broken lines form no part of the claimed design.

1 Claim, 4 Drawing Sheets---
